ATTORNEY

UNITED STATES PATENT OFFICE.

FRANKLIN DOMINICK, OF YONKERS, NEW YORK.

WINDOW SCREEN.

Application filed May 14, 1927. Serial No. 191,369.

This invention relates to an improved window screen and has for an object to provide an improved construction for a window screen adapted for use on houses or other places, the structure being such that part is permanently secured in place and part is disengageably connected to the window frame.

Another object of the invention is to provide a window screen, wherein means are associated with the netting for maintaining the netting under a continuous tension.

A still further object of the invention is to provide a window screen which includes a set of fittings adapted to be associated with a strip of netting, the arrangement being such that the netting may be applied or removed at any time and fittings may be furnished and a netting secured from a different source and assembled by the purchaser.

An additional object is to provide a window screen, wherein the parts are so formed that the netting is held only at the top and bottom edges and the holding means are disengagably associated with the window frame.

Another object of the invention is to provide a screen which can be released at the bottom in order to be swung outwardly for cleaning windows, without the screen coming off while in outward position.

In the accompanying drawing—

Figure 1 is an elevation of a window screen, disclosing an embodiment of the invention, the same being associated with a window frame.

Figure 2 is a rear view of the structure shown in Figure 1.

Figure 3 is a sectional view through Figure 1 on line 3—3.

Figure 4 is a fragmentary sectional view similar to the upper part of the structure shown in Figure 3 but with the parts swung outwardly.

Figure 5 is a fragmentary view of the upper part of the structure shown in Figure 1 with certain parts broken away for illustrating the construction of one of the springs and associated parts.

Figure 6 is a fragmentary sectional view similar to the lower part of Figure 3, but showing a slightly modified construction.

Referring to the accompanying drawing by numerals, 1 indicates an ordinary window frame of any kind, the same being provided with a sill 2 of any desired kind and a top board 3 at the upper end. A pair of specially

made hooks 4 are secured to the top board 3 by screws or other means, each of said hooks having a rather extended entrance section 5 and an arc-shaped section 6 somewhat depressed from the entrance section 5, whereby the transverse bar 7 of the respective springs 8 may snugly fit into the section 6 and be held resiliently against removal. As both hooks 4 and both springs 8 and associated parts are identical, the description of one will apply to both.

As indicated in Figure 5, the springs 8 are provided with a pair of resilient arms 9 and 10 having curved ends pressing against the top wall 11 of the channel member 12. This channel member is provided with a notch 13 through which the legs 14, merging into bar 7, extend. The channel member 12 merges into a substantially reverse channel member 15 adapted to receive one end of the wire mesh 16, which end is clamped in place by a bar 17, held in place by any desired number of screws or bolts 18. The screw or bolt 18 opposite the spring 8, preferably extends through one end of a handle member 19 which may be turned to a horizontal position as shown in Figures 2 and 3, or to a substantially vertical position as shown in Figure 4. When in a horizontal position, the handles are out of the way, but when turned to a vertical position, they may be readily grasped for forcing the bars 7 over hook 4 to apply the screen or to remove the screen. By providing the channel member 15, clamping bar 17 and associated parts, the entire upper edge of the mesh or screen 16 is clamped firmly in place without the use of solder or other securing means. Also, this arrangement permits the netting or screening to be quickly removed at any time and replaced if desired, or a new wire mesh substituted.

At the lower edge of the wire mesh or window screen 16, is a plate 20 having at its extreme lower edge a hook 21 and adjacent its upper edge a channel member 22, similar to the channel member 15. A clamping bar 23, similar to clamping bar 17, is provided and held in place by suitable screws 24. In addition to these screws, screws 25 extend through a plate 26 and a fitting 27 for holding the fitting or plate in position. Fitting 27 is provided with a substantially tubular portion for receiving the vertical end section 27 of the handle or grip 28. If desired, only one of these handles or grips could be provided,

though preferably two are used as shown in Figure 2, whereby when these two grips are moved to the dotted position shown in Figure 3, the plate 20 may be forced downwardly for applying or removing the same. Co-acting with the hook 21 is a hook 29 formed from one edge of plate 30, which plate is secured to the sill 2 by any suitable means, as for instance, screws 31. When the parts are in the position shown in Figures 2 and 3, the handles or grips 28 are grasped and pushed downwardly and outwardly, whereupon the wire mesh 16 will yield by reason of this spring action sufficiently to permit hook 21 to be disengaged from the hook 29. This loosens the lower end so that the parts may be swung out to the position shown in Figure 4 for washing windows or for throwing objects out of the window. When the parts are to be disconnected, the structure is swung from the position shown in Figure 4 to a substantially vertical position and then urged outwardly with a slightly downwardly swinging movement whereby the bar 7 is forced over the raised portion of hook 4. In performing this action, the handles 19 are grasped near the lower ends and then pulled downwardly and at the same time pressed outwardly for causing the bar 7 to slip off of the hook 4. In this way, all of the screen is removed except the two hooks 4 and plate 30 with its hook and securing screws 31. These members are left permanently in place so that the screen may be placed in position quickly at any time. In the accompanying drawing, a bar 17 has been shown, and this bar has been illustrated as rectangular as this form of bar has proven to be satisfactory, though other means could be used, as for instance, an ordinary flat plate or a U-shaped plate.

In Figure 6, a modified form is shown, wherein the bar 17' is used, said bar being round in cross section but otherwise functioning identical with bar 17. Under some circumstances, it may be desired to solder the ends of the wire mesh in place, and when this is the case, the bars 17 and 17' are eliminated and the wire mesh soldered directly in place. As indicated in Figure 1, two springs are

disclosed with their bars 7, but it is evident that more could be used if desired without departing from the spirit of the invention and in fact, more will usually be provided where the window is comparatively wide.

What I claim is:

1. In a window screen, an upper frame section having a turned over portion with a notch, and a pull spring for said notch, said spring being formed with a substantially U-shaped portion extending through the 80 notch, and a pair of laterally extending spring arms for resiliently holding the U-shaped portion in a given position.

2. In a window screen, an upper frame section having a channel portion and a turned 65 over portion, a bar co-acting with said channel portion for clamping part of a strip of netting in the channel, and a pull spring arranged in said turned over portion, said spring having a substantially U-shaped section 70 projecting from the turned over portion whereby it may be connected with a support and resiliently support said section.

3. In a window screen, an upper frame section including in its construction a looped- 75 over portion having a notch in the upper edge, and a spring associated with said notch, said spring having a U-shaped portion extending normally slightly through said notch, and a pair of resilient arms having the ends 80 frictionally engaging the top of the looped portion of said upper frame section so as to resiliently hold the U-shaped portion normally in a retracted position.

4. In a window screen, a frame having a 85 substantially hollow upper frame section, said section being formed with an opening, a pull spring arranged in said section, said spring having a substantially U-shaped center with laterally extending arms projecting 90 from the end of each leg with the ends of the respective arms positioned to normally engage that part of said section having said opening whereby said arms will resiliently resist movement of said U-shaped center 95 through said opening.

FRANKLIN DOMINICK.
